VAPORIZER FOR REFRIGERATING APPARATUS

Filed Sept. 22, 1928

UNITED STATES PATENT OFFICE

FRANKLIN G. SLAGEL, OF BUFFALO, NEW YORK, ASSIGNOR TO FEEDERS MANUFACTURING COMPANY, INC., OF BUFFALO, NEW YORK, A CORPORATION OF NEW YORK

VAPORIZER FOR REFRIGERATING APPARATUS

Application filed September 22, 1928. Serial No. 307,738.

This invention relates to the vaporizer of a refrigerating apparatus used principally for domestic refrigeration and more particularly to the valve mechanism and gas and oil outlets of the same.

5 In vaporizing chambers for use in connection with a refrigerant of low specific gravity, such as methyl chloride, the float which controls the inlet valve usually is too heavy inasmuch as it sinks into the liquid refrigerant and therefore does not close the valve tightly when the normal liquid level has been attained, it being necessary to make the float sufficiently heavy in order to avoid collapse under the pressure to which the same is subjected, this pressure at times being approximately one-hundred and fifty pounds.

10 One of the objects of this invention is to provide means for rendering the valve mechanism more sensitive and permit of closing the same tightly and still use a comparatively heavy hollow sheet metal float capable of resisting crushing under the usual high pressures to which the same may be subjected. This particular object is accomplished by 15 counterbalancing the weight of the float thus rendering the same more buoyant and quickly responsive to variations in the liquid level of the vaporizing tank or chamber so that when the liquid level drops below normal the inlet valve will be opened and admit additional refrigerant and when the normal liquid level has been restored the inlet valve will be tightly closed and thus ensure more 20 uniform operation of the refrigerating apparatus.

25 It has been found that a fixed position of the oil outlet opening in the gas outlet tube is not satisfactory due to the fact that the liquid level of the refrigerant in the vaporizing chamber varies depending on the character of the refrigerant, this level being comparatively low when using sulphur dioxide, and comparatively high when using methyl 30 chloride.

Another object of this invention is to provide means whereby the oil outlet may be readily and conveniently adjusted to suit the particular refrigerant which is used. To that 35 end this invention provides the gas outlet of

the vaporizing chamber with a separate oil outlet tube which can be bent to raise or lower its inlet end to suit the liquid level of the particular refrigerant which is used.

In the accompanying drawings:

55

Fig. 1 is a vertical longitudinal section of a vaporizing tank or chamber equipped with my improvements.

Fig. 2 is a fragmentary top plan view of the valve casing and lever forming part of the 60 valve mechanism.

Fig. 3 is a sectional end view of the outlet end of said gas and outlet pipes.

Fig. 4 is a cross section on line 4-4 of Fig. 1.

65

In the following description similar characters of reference indicate like parts in the several figures of the drawings.

The numeral 10 represents the vaporizing chamber or tank the lower part of which contains the liquid refrigerant which is exposed by means of tubes 11 or otherwise to the space to be cooled and the upper part of the chamber containing the gas or vapor resulting from the raising of the temperature of the liquid refrigerant due to the exposure of the tubes 11 to the atmosphere in the space to be cooled. On its front side this chamber is preferably provided with a removable head 9 whereby access to the interior of the chamber is accomplished when desired.

70 The gas resulting from the heating of the liquid refrigerant is discharged through an outlet conduit 12 which is formed in the head 9 and which carries the same to a condenser whereby the heat is abstracted from the gas and the same is liquefied preparatory to being used over again.

75 As the conversion of the liquid refrigerant into gas in the chamber progresses and the liquid level therein drops below a normal or predetermined level additional liquid is admitted into the chamber by a float controlled valve mechanism which embodies my invention and which is preferably constructed as follows:

80 The numeral 13 represents the body or casting of the liquid refrigerant inlet valve which is formed on the head 9 and which has a port 14 leading to the interior of the chamber and

100

terminating in an inwardly facing valve seat 15. The outer end of this port 14 may be connected in any suitable manner for example by an inlet conduit 8 with the compressor or 5 other parts of the apparatus which supply the liquid refrigerant. The passage of liquid refrigerant through the valve casing into the vaporizing chamber is controlled by a movable closure member 16 having preferably the 10 form of a needle movable lengthwise toward and from the seat 15, which valve closure is guided in a sleeve 17 forming part of a bracket 18 which is secured to the inner side of the head 9 of the vaporizing chamber by screws 15 19, as shown in Figs. 2 and 4.

The movement of the valve closure toward and from its seat is effected by a float operated mechanism which embodies my invention and which is preferably constructed as 20 follows:—

Pivotedly mounted on the inner end of the valve casing is a vertically swinging lever having preferably the form of an elbow and comprising a lower horizontal arm 20 projecting lengthwise away from the valve casing and the axis of the lever and an upright arm 21 projecting upwardly from the outer end of the lower arm and the axis of the lever. The elbow at the junction of these arms is 25 arranged between two lugs 22 on the inner end of the guide sleeve 17 and pivoted thereto by a transverse horizontal pin 23.

On the inner extremity of the lower horizontal arm of the shifting lever is mounted a 30 float 24 which is preferably made hollow and watertight of sheet metal but any other form of float may be employed which has the requisite buoyancy.

The upper arm of the shifting lever is provided with a recess 7 which receives the inner 35 end of the valve and the latter is connected with this arm by a transverse coupling pin 25. This float rises and falls in response to variations in the level of the liquid refrigerant in which the same rests which motion is 40 transmitted by the shifting lever to the valve so that the valve is opened when the level of the liquid refrigerant drops below normal and thereby admits additional liquid refrigerant to flow into the tank or chamber, and when sufficient liquid has been supplied to the 45 chamber to restore the normal level then the rising float turns the lever so as to close the valve and shut off the further supply of liquid refrigerant to the chamber. Downward motion of the float is limited by means of a 50 horizontal stop lug 26 projecting from the elbow of the shifting lever outwardly toward the valve casing and adapted to engage a stop face 27 on the underside of the guide sleeve.

When using a liquid refrigerant which is 55 low in specific gravity such as methyl chloride, the pressure in the vaporizing tank is comparatively high and the float sinks deeper in the liquid, but when using a liquid refriger-

rant which is high in specific gravity, such as sulphur dioxide, the pressure in the tank is lower and the float sits higher in the liquid. Due to the high pressure in the tank when using methyl chloride the float must be made sufficiently strong to withstand this pressure and this necessitates making the same fairly heavy. It follows therefore when using methyl chloride as the refrigerant that the valve is not closed tightly and the admission of liquid refrigerant to replenish the tank is not accurately controlled.

In order to compensate for the necessarily heavy float under these conditions a counterbalance is provided to assist the buoyancy of the float, which counterbalance preferably consists of a weight 28 arranged on the upper arm of the shifting lever and projects outwardly from the same toward the valve casing or in other words from that side of the axis of the lever opposite to that from which the float projects.

By this means the counterweight adds its lifting effect to the buoyancy of the float which otherwise would rest deeper in the liquid refrigerant, thereby compensating for the comparatively low specific gravity of methyl chloride or similar refrigerant and permitting the inlet valve to be closed tightly when the normal liquid level has been reached and also permitting a sufficiently heavy float to be used to withstand crushing pressures.

The gas or vapor resulting from raising the temperature of the liquid refrigerant is carried from the upper part of the vaporizing chamber to the outlet conduit 12 by a gas outlet tube which has a main horizontal body 29 connected at its outer end with the outlet conduit 12 while its inner part or end is turned up, as shown at 30, Fig. 1, so as to 100 avoid the entrance of foam into this tube.

In refrigerating apparatus of this character the lubricating oil of the compressor is usually delivered with the liquefied refrigerant to the vaporizing tank and means have heretofore been provided for returning this oil to the compressor by providing the gas outlet tube with an oil return opening inside on a line with the strata of oil floating on top of the liquid refrigerant in the tank. Inasmuch, however, as this oil return opening was in a fixed position the same did not function satisfactorily when using different kinds of liquid refrigerants either alone or in connection with different kinds of lubricating oils, 110 because the liquid level varies in accordance with the kind of liquid refrigerant used and also whether lubricating oil is used in connection with the refrigerant, as well as the character of the oil.

It is therefore proposed to provide an outlet for the vaporizing tank which is capable of vertical adjustment relative to the liquid level in the tank. The preferred means for accomplishing this purpose consist of a bend-

able oil outlet tube which is separate from the gas outlet tube and comprises a main horizontal part 31 which is arranged lengthwise along the bottom of the horizontal part 5 of the gas outlet tube and opening at its outer end into the main outlet conduit 12 while the inner end 32 of this oil outlet tube is bent downwardly and projects through an opening 33 in the inner part of the gas outlet tube 10 into the strata of oil lying at the top of the liquid refrigerant in the tank. This oil outlet tube may be secured in position within the gas outlet tube in any suitable manner but preferably by bending a loop 34 upwardly 15 out of the metal at the outer end of the gas outlet tube, inserting the outer end of the oil outlet tube in said loop, and securing these two tubes together by solder on the underside thereof, as shown at 35, or by any other suitable means.

During the operation of the vaporizer the preponderating pressure of the gas within the tank against the large area of the liquid exposed outside of the inlet 32 of the oil tube 20 as compared with the relatively small area of liquid exposed to gas pressure within this inlet forces the oil on the surface of the liquid refrigerant upwardly through the depending inlet of the oil outlet tube and thence horizontally outward through the main part of the same to the main outlet conduit where it joins the gas discharged from the vaporizing tank and returns with the same to the condenser and compressor for recirculation in a 25 manner common to this type of apparatus.

The oil outlet tube is made of malleable metal so that the inlet end thereof can be bent and either raised or lowered to suit the level of the oil in the tank in accordance with the 30 particular kind of liquid refrigerant or the character of the oil which is used. It is therefore possible to make this vaporizing chamber and the fittings therein all of uniform or standard construction and still permit the 35 same to be readily easily and conveniently adjusted to suit different conditions without increasing the cost of the apparatus.

I claim as my invention:

1. A vaporizer comprising a vaporizing 50 chamber, a liquid inlet valve having a casing provided with an inlet port, a movable valve closure for controlling said port, a vertically swinging lever having an upright arm connected with said valve closure and a horizontal arm, a float mounted on said horizontal arm, and a counter-balance weight mounted on the upright arm of said lever and projecting in a direction opposite to the float.

2. A vaporizer comprising a vaporizing 60 chamber, a refrigerant valve having a casing mounted on said chamber and provided with an inlet port and a stop face, a valve closure movably mounted on said casing and controlling said port, a vertically swinging lever pivoted on said casing and operatively con-

nected with said valve closure and having a lower horizontal arm projecting away from said casing, a stop lug projecting horizontally toward said casing and adapted to engage with the stop face thereof, and an upper upright arm projecting upwardly from the axis of said lever, a float mounted on the lower arm of said lever, and a counter-weight mounted on the upper arm of said lever and projecting toward said valve casing.

3. A vaporizer comprising a vaporizing chamber, means for controlling the admission of refrigerant to said chamber, a gas outlet conduit communicating with said chamber, a bendable oil outlet tube communicating 75 with said gas outlet conduit and adapted to be bent for adjusting its inlet end relative to the liquid level in the chamber.

4. A vaporizer comprising a vaporizing chamber, means for controlling the admission 85 of a liquid refrigerant into said chamber, a gas outlet conduit having a tube arranged within the chamber and provided with an upturned inlet end, and a bendable oil outlet tube passing through the wall of said gas outlet tube and having a downwardly projecting inlet end capable of being bent to change the position thereof relative to the liquid level in the chamber and an outlet end arranged within the gas outlet tube and projecting 90 toward the outlet end of the latter.

5. A vaporizer comprising a vaporizing chamber, means for controlling the admission of a liquid refrigerant into said chamber, a gas outlet conduit having a tube arranged 100 within the chamber and provided with an upturned inlet end, a bendable oil outlet tube passing through the wall of said gas outlet tube and having a downwardly projecting inlet end capable of being bent to change the position thereof relative to the liquid level in the chamber and an outlet end arranged within the gas outlet tube and projecting toward the outlet end of the latter, and an upwardly bent loop which is formed out of the 105 lower part of the outlet end of said gas tube and which receives the outlet end of said oil tube.

In testimony whereof I hereby affix my 110 signature.

FRANKLIN G. SLAGEL.
